UNITED STATES PATENT OFFICE.

MAXIMILIAN W. OBERMILLER, OF NEW YORK, N. Y.

NOTE-SHEET-CONTROL MECHANISM.

1,362,262.

Specification of Letters Patent. Patented Dec. 14, 1920.

Application filed January 27, 1920. Serial No. 354,378.

To all whom it may concern:

Be it known that I, MAXIMILIAN W. OBERMILLER, a citizen of the United States of America, residing at New York city, State of New York, United States of America, have invented certain new and useful Improvements in Note-Sheet-Control Mechanism; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My invention relates to note-sheet control mechanism, to maintain the note sheets of pneumatically operated musical instruments in proper tracking relation to the tracker bar, whether the tracker bar is moved for transposition of the music or not, or for registering the webs of web printing presses.

It is immaterial to what kind of pneumatic musical instrument my invention is applied, whether for pneumatically played violins, pianos or other instruments operated by pressure air or by suction.

In order that my invention may be fully understood I have illustrated it diagrammatically as applied to a pneumatically played piano.

Referring to the drawings, in which like parts are similarly designated—

Figure 1 is a diagrammatic view of so much of a player piano as is necessary for an understanding of my invention.

Fig. 2 is a view, partly in section, looking from the right of Fig. 1, of the pumping devices.

Fig. 3 is a detailed view, on a larger scale, with parts in section, of the mechanism at one end of the tracker bar.

Fig. 4 is a cross-section through the feeler valve, showing the valve stem guide.

Fig. 5 shows my invention operated by suction instead of pressure.

In my experiments with note sheet control mechanisms I have found that a quicker and more sensitive operation can be obtained in connection with valve actuated control mechanism by using air under pressure, rather than by vacuum, as is now commonly done. The pressure, ordinarily, need not be over half a pound in excess of atmospheric pressure.

An objection to present control apparatus is the difficulty in supplying slight lateral movement to the music sheet when deviating from normal tracking, and that the control is not sensitive enough, for the reason that the sheet, either directly or indirectly, causes the uncovering of a port, and that the area of the tracker port uncovered is the measure of the admission of air, so that a full or nearly full opening of the port is necessary before the music sheet is shifted back to normal position.

I overcome this by having means for opening a large area for the passage of air for the control apparatus for a very slight lateral deviation of the music sheet, adjustable to a lateral movement of the music sheet of about fifteen one-thousandths of an inch, so that the music sheet will for the slightest lateral movement be shifted back to normal position.

Another objection to many pneumatically played pianos is that when the edges of the sheet become worn, or torn, the sheet is continually moved back and forth along the tracker due to the uneven edges. This also I avoid by my construction.

Other advantages of my construction will hereinafter be stated in connection with the detailed description.

Referring to Fig. 1, the pedals 1, 1, are connected by a bent rod 2 to the main vacuum bellows 3, 3, connected to an evacuating reservoir 4 that is connected with a tension equalizing chamber 5, as is customary.

According to my invention I mount on the reservoir 4 or at any other convenient place a pressure pumping bellows 6 connected to one of the rods 2 in any suitable manner, whereby pressure air is pumped through tube 7 to a pressure chamber or reservoir 8 mounted on the side 9 of the piano case. This reservoir is provided with a non-return valve 10 and a compression spring 11 and supplies air under pressure through tube 12 to a valve chest 13.

The valve chest has a pressure chamber 14, and two like sets of valves, each set controlling a bellows. One valve set, comprising valves 15 and 16, controls the admission and release of pressure air to chamber 17, the valve 15 controlling port 15^a between the chambers 14 and 17, and the valve 16 controlling the release of pressure air from chamber 17 through port 16^a, to the exhaust

chamber 18 common to both sets of valves and connected by a port 19 to the atmosphere.

The two valves 15 and 16 are preferably loosely mounted on the same stem 20 guided in guides 21 and 22, the stem at its lower end being secured in a wooden pad or rest 23 supported on a thin diaphragm 24 covering a chamber 25 that is connected by tube 10 26 to the right hand feeler valve 27.

The chamber 17 is connected by a port 28 to a bellows 29.

The other set of valves is similar to those just described, and comprises a valve *a* controlling a port *b* between chamber 14 and a chamber *c*. A valve *d* controls a port *e* between chambers *c* and 18. The two valves are identical in construction with those 15 and 16; are mounted on a single stem suitably guided, and carry a pad *f* resting on a diaphragm *g* of pressure chamber *h* that is connected by a tube 30 to the left hand feeler valve 31. The chamber *c* is connected by a port *i* with a bellows 32.

25 The chambers 25 and *h* are provided with so-called "leakage openings" 39, which are fine pin holes at the end of a passage 40 leading from the pressure chamber 14 to the diaphragm chambers, so that the diaphragms 30 are always under pressure, unless one of the chambers, 25 or *h*, is vented through a feeler valve.

The two bellows 29 and 32 are connected together by a link 33, and the bellows 32 is connected by a rod 34 to a lever system, 35, 36, 37. The end of the lever 37 contacts with the end of spindle *S* of one of the music rolls and operates this spindle longitudinally in conjunction with the usual sprung urged bearing 38 at the other end of the roll, whereby the roll is shifted slightly in one direction or the other to correct abnormal tracking of a music sheet.

The feeler valves, Figs. 3 and 4, consist 45 of a tube 31 interiorly threaded for a portion of its length at 41 for the reception of a guide 42 having ports 43 and a screw-driver groove 44. In the end of the tube 31 is screwed the valve seat 45 having a large bore 46 communicating with a smaller bore 47 for the valve stem 48. The large bore 46 communicates with vents 49 leading to the atmosphere. The valve stem is guided at one end in the guide 42, and near the 55 other end in the valve seat, and carries a cone valve 50 that is seated by a light spring 51 surrounding the valve stem 48 and having bearing at one end against the guide 42 and at the other end against the valve 50. 60 The valve stem 48 carries at its end the feeler head 52 of mushroom shape, the central portion 53 of the surface being flat. This head and spindle are free to rotate, and should the edge of the paper music 65 sheet ride on the curved portion of the head,

the valve will rotate without injuring the edge of the music sheet.

Ordinarily the edge of the music sheet will contact with the flat portion 53 of the mushroom head to move the valve 50 off its seat and vent the air pressure in chamber 25 or *h* to the atmosphere.

It will be noted that the construction is such that a very slight movement of the valve off its seat will give a comparatively large area for venting through the valve seat. The movement of a few thousandths of an inch will give a port opening of from four to ten, or more, times the area of the pin-hole leakage ports 39. In order to obtain a quick action, the area opened by the valve must always be considerably larger than the leakage ports and this area can be proportioned to suit any conditions by varying the size of the valve seat so as to give a 85 larger or smaller peripheral space between the valve and seat for a given depression of the feeler head.

The tubes 31 are mounted independent of the tracker bar *T*, and to this end this bar 90 is provided with slots 54 in its ends. This bar has secured at one end a threaded bolt 55 on which is rigidly held one end of an arm 56 between two nuts 57. Through the other end of this arm passes a thumb-screw 95 58 mounted to rotate in the frame *F* of the tracker bar and note sheet rolls.

The tracker bar is provided with a series of indices or marks 59, usually three on each side of a central mark. The distance between adjacent marks is equal to that between adjacent tracker bar openings, so that by adjusting the tracker bar to the right or to the left the music may be played from one to three notes higher or lower than the 105 normal key indicated by the central mark.

According to my invention an index finger 60 is placed on one of the straps 61 that hold the tracker bar *T* to the frame *F*. This strap is stationary, and on the under 110 surface of that portion of the strap that presses over the slot 54 in the tracker bar is secured a split screw sleeve 62 in which the feeler valve tube 31 is frictionally held by a nut 63, so that the tube 31 115 may be readily adjusted to the width of the note sheet. The tube 27 at the opposite end of the tracker bar *T*, Fig. 1, is similarly mounted on the strap 61.

The operation is as follows:

As soon as the edge of the note sheet touches the flat end surface 53 of the mushroom feeler head of feeler 31 and moves this head a few thousandths of an inch, the valve 50 is opened sufficiently to vent the 125 pressure from chamber *h*, tubes 30 and 31, through the valve seat and ports 49 to the atmosphere. Diaphragm *g* collapses opening valve *a* and closing valve *d*, thus admitting pressure air from chamber 14 to 130

chamber *c* through port *i* to the bellows 32, inflating this bellows, which operates the rod 34 and lever system 35, 36 and 37, to remove pressure from the music roll spindle *S* and permit spring 38 to move the music roll to the right. The bellows 32 being connected by rod 33 to bellows 29, this bellows is deflated by the pull of bellows 32, the air being vented through port 28, open valve 16, chamber 18 and port 19 to atmosphere.

As soon as the edge of the music sheet has left the feeler head, the valve 50 closes and chamber *h* fills with pressure air through leakage port 39 lifting the diaphragm, closing valve *a* and opening valve *d* to vent chamber *c* and the bellows 32 into chamber 18, and through port 19 to the atmosphere.

When feeler 27 is operated by the opposite edge of the sheet, chamber 25 is vented, closing valve 16 and opening valve 15 to admit pressure air from chamber 14 to chamber 17, thence through port 28 to bellows 29 to inflate the latter, thus causing a pull on link 33 collapsing bellows 32, pulling rod 35 and the lever mechanism to cause lever 37 to exert pressure on music roll spindle *S* to urge the roll to the left against the action of spring 38.

Should a portion of the edge of the sheet be torn away there will be no contact at this point with the feeler head and the valve remains closed and will be operated only when the normal edge of the music sheet tracks past the feeler.

Should the music sheet ride up onto the feeler head 52, the head and valve stem are free to revolve so that the sheet will not be torn, as the head acts as a roller and the normal tension on the sheet soon causes the edge of the sheet to ride down the curved surface of the head toward normal position, and at the same time opens the valve to cause the movement of the music roll, as heretofore described.

It will be noted that the valve stem is guided at both ends. This arrangement insures opening even when the pressure is on the underside of the mushroom feeler head, and prevents tilting and binding. The stem is also comparatively long to insure movement under all conditions of operation.

In Fig. 5 I have shown the valve chest 13 arranged for suction instead of pressure, the only change made being that port 19 is connected directly to the vacuum chamber 4 by pipe 12, chamber 14 is vented to the atmosphere, and the leakage ports 39^a leak into chamber 18; all other parts are the same as heretofore described with reference to Fig. 1.

Operations of pneumatic mechanism by suction are so well understood it is believed that no detailed description will be neces-

sary. The feeler valves admit atmospheric air to the evacuated chambers *h* and 25 to operate valves 15 and 16 and *a*, *d*, to evacuate the respective bellows, which are normally under atmospheric pressure. The lever mechanism, 35, 36 and 37 is then operated as before described.

I claim—

1. The combination with a tracker bar; of a feeler valve comprising a rotatable feeler head, a valve positively connected to said head and pneumatic mechanism controlled by said valve to adjust the tracking of the music sheet.

2. The combination with a tracker bar; of a feeler valve positioned for contact by the edge of a note sheet, comprising a spring-urged rotatable spindle, a feeler head on said spindle and a valve on the spindle controlling the passage of air, and pneumatic mechanism controlled by said valve to adjust the tracking of the music sheet.

3. The combination with a tracker bar; of a feeler valve positioned for contact by the edge of a note sheet, comprising a tube, a spring-urged valve in said tube, a valve seat on the end of said tube having a large number of lateral air ports therein, a valve spindle passing through said seat and a sheet contacting head on said spindle.

4. The combination with a tracker bar; of a feeler valve positioned for contact by the edge of a note sheet, comprising a rotatable head, a tube, a valve in said tube, a spindle for the valve and head, a spindle guide in the tube, and a spring on the spindle between said guide and tube.

5. The combination with a tracker bar; of a feeler valve positioned for lateral contact by the edge of a note sheet comprising an air tube, a valve seat member in threaded connection with one end of said tube having a central valve stem passage ported to the atmosphere, a valve stem loosely passing through said passage, a mushroom head on one end of said stem, a guide within said tube for guiding the other end of said stem, a valve on the stem for closing said passage and a spring for urging the valve onto its seat.

6. The combination with a tracker bar; of a strap for holding the end of said bar, and a feeler valve for note sheet adjusting mechanism secured to said strap.

7. The combination with a tracker bar; of a strap for holding the end of said bar and a feeler valve for note sheet adjusting mechanism adjustably secured to said strap.

8. The combination with a tracker bar having longitudinal recesses in its ends and means for shifting said bar for transposition of the music; of straps for holding said bar, and feeler valves secured to said straps and lying within said recesses.

9. The combination with a tracker bar

having longitudinal recesses in its ends, and means for shifting said bar for transposition of the music; of straps for holding said bar, and feeler valves adjustably secured to said 5 straps and lying within said recesses.

10. The combination with a tracker bar having longitudinal recesses in its ends and means for shifting said bar for transposition of the music; of straps for holding the 10 ends of said bar traversing said recesses, split screw sleeves on the under sides of the straps and lying in said recesses, feeler valves in said sleeves and nuts on said sleeves for clamping said feeler valves in the sleeves.

15. 11. In a pneumatic player piano; a tracker bar holding strap having a transposition indicating pointer projecting therefrom adjacent an edge of the tracker bar, a threaded split sleeve secured to the under face of said 20 strap and a clamping nut on said sleeve.

12. In a pneumatically operated musical instrument, main suction producing mechanism for the instrument, in combination with note sheet control mechanism operated 25 by pressure air, including pressure air pumping mechanism operated from the main suction producing mechanism.

13. In a pneumatically operated musical instrument, main suction producing mechanism, comprising a main reservoir, a tension equalizer therefor, suction bellows for ex-

hausting the reservoir, and pedals for operating said bellows; in combination with a pressure pump mounted on said reservoir and operated by said bellows, a pressure air 35 reservoir supplied by said pump, and note sheet control mechanism connected to said pressure air reservoir.

14. In combination, a tube, a valve seat member in one end of said tube and having 40 a central bore and a valve seat on its lower end, a valve stem loosely passing through said bore, a valve on the stem, a stem guide in the other end of the tube and a spring surrounding the stem between the guide and 45 valve.

15. In combination, a tube, a valve seat member screwed into one end of said tube and having a central bore terminating below in a conical valve seat and having at its upper end transverse ports to said bore, a valve 50 stem guided in said bore, a conical valve on the stem, a stem guide in the lower end of the tube, and a long coil spring between said guide and valve and a head on the valve stem 55 to actuate the same, said stem, valve and head being free to rotate.

In testimony that I claim the foregoing as my invention, I have signed my name hereto.

MAXIMILIAN W. OBERMILLER.
